CUP AND SAUCER HOLDER

Harvey R. Avedon, Pacific Palisades, Calif., assignor to Alladin Plastics, Inc., Gardena, Calif., a corporation of California

Filed Mar. 18, 1968, Ser. No. 11,020

Term of patent 14 years

Int. Cl. D6—01

U.S. Cl. D44—29

The essential features of the design reside in the particular arrangement of the upper face and the cut-outs.

I claim:

The ornamental design for a cup and saucer holder, as shown and described.
